HEEL TREATING

Kenneth W. Macdonald, Watertown, Mass., assignor to Compo Shoe Machinery Corporation, Boston, Mass., a corporation of Delaware

Application November 12, 1940, Serial No. 365,320

52 Claims.

(Cl. 12—42)

This invention relates to heel treating machines for use in the manufacture of footwear, and more particularly to fastener inserting heel attaching machines.

A general object of the invention is to provide an improved form of machine for inserting a fastener through the heel seat of a shoe and into the heel to hold the latter permanently in place.

More particularly, objects of the invention are to provide a heelining machine which is largely automatic in its operation, and which is adapted to be worked through simplified controls which enable a moderately skilled operator to fasten heels to shoes quickly and accurately.

Further objects of the invention are to provide a machine for inserting a fastener in the form of an inexpensive standard wood screw in a wood heel while the latter is clamped to a lasted shoe, which holds the heel to the shoe during subsequent pounding up and other finishing operations before the shoe is delasted.

Other objects of the invention are to provide an improved heelining machine wherein a heel is held clamped against the heel seat of a shoe, and means are provided for first drilling a hole through the shoe heel seat and into the heel, and then driving a fastener into such drilled hole to attach the heel and heel seat portion of the shoe together. Specific objects are to provide such a machine wherein the clamp, drill, and driver are all movably interrelated, and arranged automatically to assure proper positioning of the fastening screw both as to its location on the heel seat and the depth to which it is driven. Further specific objects are to provide such a machine wherein the drill and driver are both directed through their cycle of operations by manipulation of a single manual control, and wherein the clamp is opened and closed by a single treadle control, whereby the operator can load, treat, and unload shoes with great speed and facility and with minimized need for close attention or high skill.

Up until the time of the present invention, it has been the most widespread practice to hold the heel to a lasted shoe with a temporary skewer which draws the heel against the last and holds it during the finishing operations, such as pounding up, breast flap laying and trimming, top-lift edge trimming, etc. Such skewer must be removed to delast the shoe.

In factories desiring a firm attachment between heel and shoe, a permanent wood screw is inserted in addition to the usual five heelining nails, after the shoe is delasted. To save expense,

many other factories dispense with this permanent screw and rely merely on the heelining nails, thus obtaining a relatively weaker shoe. In accordance with the objects of this invention, provision is made for rapidly and efficiently driving a headed permanent wood screw into the shoe and heel while the shoe is still lasted, thus providing at reduced expense and with a reduced number of total operations a shoe having the advantages as to screw heel attachment during finishing operations plus the superior permanent screw attachment in the finished shoe which the practice heretofore in common use afforded only through separate and cumulative skewering and screwing operations.

Yet further objects are to provide a fastener inserting heelining machine having a hollow last jack-pin capable of affording passage to a drill and to a fastener and its driver, in combination with a last having an improved jack-pin hole construction cooperable with such machine, and to provide such lasts for this use.

Additional objects are to make a heel attaching machine capable of largely automatic operation, wherein the mechanism is ruggedly constructed and compactly and attractively housed.

Other objects of the invention will in part be obvious and will in part appear hereinafter.

The invention accordingly comprises the features of construction, combination of elements, and arrangement of parts, which will be exemplified in the construction hereinafter set forth and the scope of the invention will be indicated in the claims.

For a fuller understanding of the nature and objects of the invention reference should be had to the following detailed description taken in connection with the accompanying drawings, in which:

Fig. 1 is a front elevation of a heel attaching machine embodying principles of the invention, the outer sheathing being broken away to show the interior mechanism;

Fig. 2 is the side elevation of the machine of Fig. 1 viewed from the right of that figure;

Fig. 3 is a plan view of the machine of Fig. 1, with the clamp unit hood removed;

Fig. 4 is a fragmentary front elevation, on an enlarged scale, of the upper portion of the machine substantially corresponding with line 4—4 of Fig. 2, parts being shown in section;

Fig. 5 is a fragmentary horizontal section along line 5—5 of Fig. 4;

Fig. 6 is a fragmentary side elevation of the

portion of the machine shown in Fig. 4 as viewed from the right of that figure;

Fig. 7 is a fragmentary side elevation on a further enlarged scale of the heel clamping mechanism used in the machine of Fig. 1 as viewed from the right of that figure, parts being shown in section;

Fig. 8 is a fragmentary horizontal sectional view along line 8—8 of Fig. 7;

Fig. 9 is a fragmentary front elevation along line 9—9 of Fig. 7;

Fig. 10 is a fragmentary longitudinal sectional view taken approximately medially through the upper portion of the machine and showing parts of the screw driving mechanism, some parts being shown in section;

Fig. 11 is a fragmentary front elevation on an enlarged scale along line 11—11 of Fig. 10.

Fig. 12 is a fragmentary sectional view showing a detail of the screw receiving socket;

Fig. 13 is a side elevation on a reduced scale showing the shoe and heel clamping mechanism in open position;

Fig. 14 is a side elevation similar to Fig. 13, but showing the clamping mechanism in clamping position;

Fig. 15 is a side elevation showing details of the clamping and drilling mechanism;

Fig. 16 is a longitudinal sectional view, on an enlarged scale as compared with Fig. 15, showing details of mechanism for controlling the screw driver; and

Fig. 17 is a wiring diagram showing one suitable arrangement for controlling the electrically operated parts of the machine.

The machine specifically described and illustrated herein by way of example is arranged to drive a wood screw into a lady's high wood heel. Of course, any other kind of heel capable of receiving a driven fastener, such as leather and various kinds of plastic heels, can be handled, and certain features of the invention can be applied to advantage whether the fastener is a wood screw, as preferred, or of some other type such as a nail or nails, a press driven rivet, or the like.

The machine construction is also readily adaptable to other work treating operations involving drilling or driving, such as drilling a heel and inserting a reinforcing dowel therein.

While the machine can readily be used for heelng delasted shoes, its chief benefits are obtained when the heel is attached while the shoe is still lasted on last having a special drill and screw receiving bore through the heel end thereof.

Characteristic features of the machine comprise a spring clamping unit for holding a heel in its properly located position against the shoe bottom, which clamping unit is swingably mounted on the frame of the machine and is normally biased by its spring to clamping position. In order to insert the shoe an electrically controlled lifter is provided which elevates the clamp against its bias. The shoe and heel are inserted in the opened clamp over a hollow jack pin and when thus properly positioned, the lifter is released to enable the clamp to operate under its bias to hold the parts together. Thereafter a rotating drill is elevated through the hollow jack pin and through the opening in the last so as to drill a screw receiving bore through the insole and other heel seat materials if they are present and into the heel. This drilling operation continues to a depth which may be determined by the

length of the drill shank and stops when the drill spindle, which is thicker than the shank, touches against the insole of the shoe or some other suitable abutment in the last opening. The drill is then retracted and the clamp is swung from the position it occupies during drilling to another position in registry with a screw driver. A screw is previously dropped by hand into a suitable socket in the machine frame also in permanent registry with the screw driver, which is then elevated to pick up the screw and carry it through the hollow jack pin and through the last and drive it home in the bore previously prepared by the drill. The screw driving operation continues to a depth which is controlled by the drilling operation, so that when the top face of the screw head is brought even with the plane of the upper face of the insole on the interior of the shoe, the screw driving operation stops. The driver is then retracted, the clamp elevated, and the shoe removed. After removal of the shoe the clamp automatically returns to its initial drilling position where it is again loaded for a repeated cycle of operations.

Referring more particularly to the drawings and first to Figs. 1 and 2, there is shown a machine comprising upstanding frame castings 20 and 21 resting on a suitable base which is adapted to be set on the floor. These frame castings are connected by rigidifying cross struts and supports 22 and 23 and by a horizontal upper frame casting 24 bolted to their upper ends. Suitable sheet metal sheathing 25 is preferably provided around all four sides of the machine between the base and the upper frame casting 24 to enclose most of the working parts.

Pivoted in a central vertical bearing 26 (Fig. 6) cast in the top frame 24 is a hollow vertical pivot 27 fixed to and rotatable with a clamp post 28. This post has a bottom flange 29 by which it is fixedly screwed to a swinging clamp base 30 recessed on its underside to accommodate bearing races 31 which are interposed between the swinging clamp base and the upper frame 24. Fixed to the lower end of the pivot 27 is a spring seat and collar 32, the upper surface of which slidably abuts the under face of the frame bearing 26. Thus the post 28, clamp base 30, post pivot 27, and collar 32 are fixed together as a unit and may collectively rotate in the frame bearing 26. The post 28 has a bore 33 forming a continuation of the bore in hollow post pivot 27, through which a clamp rod 34 is slidably mounted with a suitable key or spline for preventing relative rotation of the rod and post while permitting vertical sliding movement therebetween. A lifting cap 35 is screwed for vertical adjustment into the lower end of rod 34 and an internally threaded spring seat 36 is adjustably screwed to the lower end of rod 34 above the lifting cap. A strong compression spring 37 is seated between the collar 32 and seat 36 and normally tends to urge the latter and the clamp rod 34 downwardly. This spring applies the clamping pressure between the shoe and heel while the latter is being drilled and attached, and it should be able to apply a substantial pressure in order to assure firm pressing and compacting of the heel seat. In practice, a spring compressible up to 180 or 200 pounds pressure is satisfactory, but this value may be raised or lowered to fit conditions imposed by the work at hand. Attached to the upper end of the clamp rod is a clamp arm 38 held against a shoulder 39 on the rod by a nut 40. Abutment of the arm 38 against the upper face of post 28 marks

the extreme downward limit of movement of rod 34 under its spring bias. Suitable mechanism hereinafter described is provided for lifting the cap 35 and thereafter permitting it to lower in order to open and close the clamp mechanism.

The means for holding the shoe and heel clamped together is best shown in Figs. 7, 8, and 9, and includes a top-lift engaging clamp 41 and a back-heel engaging clamp 42 which are adapted to bear against a heel which is properly located by hand on the heel seat of a lasted shoe, the last of which is inverted over a short hollow last jack-pin 43 (Fig. 6) which is threaded into the clamp base 30. This base 30 is pocketed at 44 to receive a last supporting block 45 which has its under surface bevelled or somewhat V-shaped as at 46 to enable it to rock laterally within the pocket 44 in order to adapt itself laterally to any slope of the under face of the last against which it abuts; the block being cut away around the jack-pin to allow any needed tilting. The last engaging face 47 of block 45 is longitudinally sloped with respect to the vertical direction of the hollow last jack-pin 43 so that the upper face of the heel end of the last can seat fully against the block 47 and the last jack-pin hole 48 can form a vertical continuation of the hollow bore in the jack-pin 43. The last is preferably reinforced with an internal rigid metal ferrule extending entirely therethrough, the direction of which for a given run of lasts determines the angular slope 47 of the last supporting block 45. As illustrated in Fig. 10, the ferrule is preferably constricted at the end adjacent the last bottom so as to snugly but freely to guide the head of the wood screw, which is not quite $\frac{3}{8}$ inch in diameter in a preferred standard type. The other end of the ferrule is of standard jack-pin hole diameter ($\frac{1}{8}$ inch) to accommodate the jack pin 43 of the present machine as well as those on other machines used during processing of the shoe.

In order to insert the shoe and heel over the jack pin 43 the clamps 41 and 42 are respectively elevated and retracted by lifting the clamp rod 34. The top-lift clamp 41 is pivoted at 48 to a bar 49 which is press fitted to the lower end of an internally threaded slideable bushing 50 which is fitted for vertical adjustment within a bore 51 in the forward end of arm 38. This bushing is adapted to be raised and lowered within its bore by an adjusting screw 52 which is freely rotatable at 53 within the arm 38 and is provided at its upper end with a knob 54, rotation of which causes bushing 50 to raise or lower, thus adjustably determining the height of top-lift clamp 41 with respect to arm 38 and with respect to back-heel clamp 42 which is on the post 28. The bushing 50 is suitably slidably keyed within the bore 51 to prevent its rotation with respect thereto when the adjusting screw is turned. The angular position of top-lift clamp 41 can be adjusted for different styles of heels by means of an adjusting screw 55 which is threaded through the bar 49 so that its lower end can project therebelow and form a limiting abutment for the pivotally mounted top-lift clamp 41. A tension spring 56 tends normally to hold this clamp against the adjusting screw 55. The latter is freely slideable within a bore 57 in the arm 38 and a knurled rotating collar 58 is keyed to an elongate slideable keyway 59 in the adjusting screw 55 so that rotation of the collar raises and lowers the latter with respect to the threaded bar 49.

This keyway and the free slideable mounting of the adjusting screw 55 with respect to the arm 38 enables such screw to partake of any vertical adjustments imparted to the bar 49 by its adjusting screw 52.

The back-heel engaging clamp is adjustably threaded into the lower end of a retractable rack 60 which is slidably mounted in a guideway within clamp post 28. As shown, this clamp is forked somewhat to engage against the back of the heel and slightly forwardly along the sides of the heel. If wanted, the clamp can be arranged to embrace the heel laterally to any desired extent, and contact between the clamp and heel need not be confined to the back of the latter. The rack 60 is slotted at 61 and a transverse key 62 fixed to the post 28 traverses this slot and prevents rotation and also limits the extent of sliding movement of the rack 60 with respect to post 28. The toothed portion of rack 60 meshes with a pinion 63 keyed to a shaft 64 rotatable in the post 28. One end of shaft 64 has a retracting pinion 65 keyed thereto in position to be engaged by a drive rack 66. This is adapted to be lifted by the arm 38 through a bolt 67 which extends through a slot 68 in rack 66 and has a cap 69 overlapping such slot and holding the rack slidably against the arm 38. An adjustable set screw 70 is threaded into the upper end of rack 66 and projects into slot 68 in position to be engaged and lifted by bolt 67. Elevation of arm 38 accordingly will, after a short interval during which bolt 67 approaches and meets set screw 70, act through rack 66 to rotate shaft 64 and retract the back-heel clamp 42. The latter is normally biased to its downmost projected position by spring means. This comprises a projecting pinion 71 keyed on the other end of shaft 64 and positioned to be engaged by a projecting rack 72 which is slidably keyed in a spring cylinder 73 on post 28, the lower end of which comprises an adjustably threaded spring seat thimble 74. A compression spring 75 seated between this thimble and the rack 72 normally urges the latter outwardly and biases the back-heel clamp 42 downwardly against a heel except during such times as it is retracted by elevation of the clamp arm 38. Thus, when a shoe and heel are set over last jack pin 43 and clamp rod 34 is permitted to descend under its spring bias, the heel is held firmly against the inverted shoe by engagement of the top-lift clamp and back-heel clamp therewith, the pressure exerted by spring 37 being transmitted through the top-lift clamp to the lasted shoe, and in turn to the last supporting block 45 and clamp base 30. By virtue of the loose motion of bolt 67 in slot 68, the back-heel clamp 42 can yield against spring 75 when it strikes the heel, accommodating itself to a proper position with respect to the top-lift clamp for any given style of heel, and bearing against the heel with the force exerted by spring 75, which is pre-loaded to a suitable extent. The top-lift clamp 41 is vertically adjusted to engage the heel shortly after clamp 42 during descent of arm 38, to assure proper contact of clamp 42 with the rear of the heel. The arrangement also provides for retraction of the top-lift and back-heel clamps in unison during the latter portion of the top-lift clamp raising or opening movement, while providing independent spring pressure of these clamp parts under their respective spring biases 37 and 75 during the latter portion of the lowering or closing movement of the top-lift clamp. All of these parts including the clamped shoe are ro-

tatable with respect to the main frame bushing 26 on pivot 27.

The swingable clamp unit is normally held biased toward the right as viewed in Fig. 3 by means of a tension spring 76 (Fig. 5) extending between the main frame and an arm 77 projecting rearwardly from a downward extension 78 (Fig. 6) of the collar 32. Swinging movement of the clamp base is limited by a stud 79 fixed to the clamp base 30 and having its lower end operating in an arcuate slot 80 in the upper frame casting 24. When the spring 76 pulls the stud 79 into the right hand end (Fig. 3) of this slot the hollow jack pin spindle 43 is substantially in alignment with the drill mechanism.

One suitable means for raising the clamp rod 34 may comprise a motor driven hydraulic thruster which is so arranged that as long as its motor is energized and operating, fluid pressure is applied against a piston so as to project and hold projected its thrust rod which in the present drawings has been indicated at 81 (Figs. 2 and 6). Upon stopping the motor, the thrust rod settles back to its initial position. The vertical travel of the rod is confined between definite limits. Such motor driven hydraulic thrusters are commercially available in various types and their details need not be explained here. In the present machine the thrust rod 81 is, upon actuation of the thruster motor, adapted to be forced upwardly against a roller 82 carried at the end of a lever 83 keyed to a rock shaft 84 mounted in the upstanding frame members 20 and 21. Lever 83 carries a roller 85 adapted to engage and lift cap 35 on the lower end of clamp rod 34.

The shoe and heel drilling mechanism comprises a drill 86 (Fig. 4) having an exposed shank somewhat longer than the attaching screw which is to be inserted in the drilled hole, which is carried by a shouldered spindle 87 the upper shouldered end of which is, in the form illustrated, adapted to abut against the insole of the shoe being drilled at the end of the drilling operation. To this end the spindle 87 is mounted for vertical reciprocation while it rotates. The means for rotating the spindle comprises an electric drill motor 88 (Figs. 1 and 4) fixed to frame casting 21 with its drive pulley belted to a driven drill pulley 89 which is keyed to the lower end of a driving sleeve 90. This sleeve rotates within a vertical bearing column 91 which is fixedly bolted to the frame struts 22 and 23. The interior driving connection between the sleeve 90 and the twist drill spindle 89 is the same as that for the corresponding screw driver rotating mechanism and will be described in connection therewith, since these features are best shown in the sectional view of the screw driver rotating mechanism as illustrated in Fig. 4.

The screw driver's rotatable sleeve 590, which corresponds with the drill's sleeve 90, is driven by a pulley 589 belted to an electric driver motor 588 fixed to the frame casting 20. Sleeve 590 turns freely within suitable bearing bushings in the bearing column 591 and is held against vertical elevation by abutment of its pulley hub against the lower end of such column. It is held against dropping downwardly by a flange 592 around its upper end. Vertically slidable within the drive sleeve 590 is a chuck spindle 593. The drive sleeve has an elongate key-slot 594 by means of which it is slidably splined to the chuck spindle 593 so that the latter partakes of its rotary movement while remaining free to reciprocate vertically with respect thereto. The spindle 593

is attached to a vertically sliding cylindrical carriage 595, so as to partake of the vertical lifting movement of the latter, by means of an annular flange 596 near its upper end which rests on ball-bearing raceways 597, which in turn rest on a journal bushing 598 carried at the upper end of the cylindrical carriage 595. A collar 599, which spins with the spindle 593, holds the latter against riding upwardly with respect to carriage 595 by abutting the lower end of a journal bushing 600 fixed in the lower end of such carriage. The drill spindle 81, and the screw driver spindle 587, are fixed in their respective chuck spindles, such as 593.

The carriage 595 is mounted for vertical sliding movement in the extended upper end of the bearing column 591 and by virtue of its described connection with the spindle 593 serves to raise and lower the latter while it is being rotated through its sliding key connection with the drive sleeve 590.

The means for raising the carriage 595 comprises opposed trunnions 601 operating in vertical slots 602 in the walls of bearing column 591. These trunnions are respectively carried by links 603 which are pivotally suspended from rocker arms 604 which are each connected to a single rocker arm sleeve 605 (Figs. 4 and 5).

Returning to the drill mechanism, the cylindrical carriage corresponding with carriage 593 is lifted by trunnions borne by pivotally suspended links 103 which are hung from rocker arms 104 each connected with a single rocker arm sleeve 105. The rocker arm sleeves 105 and 605 are rotatably mounted in abutting relation on a rock shaft sleeve 106 which is rotatably mounted in a pair of suitable bearings 107 (Figs. 1, 4, and 5) suspended from the upper frame casting 24. The rock shaft sleeve 106 is free to turn in such bearings but is suitably collared to prevent endwise axial movement. Within the rock shaft sleeve 106 and axially slidably with respect thereto is a rock shaft axle 108 carrying a transverse clutch key 109 in the vicinity of the abutting edges of rocker arm sleeves 105 and 605. These rocker arm sleeves carry respective slots 110 and 610, and 111 and 611 (Fig. 5), which accommodate the projecting ends of key 109. The rock shaft sleeve 106 is also slotted to accommodate and permit relative shifting movement in an axial direction of such key 109. The clutch key is adapted to be selectively shifted back and forth between slots 110 and 610 by means of an operating control handle or lever 112 which is pivoted to an extension 113 (Fig. 4) on a collar 114 fixed to rock shaft sleeve 106 near its right end as viewed in Figs. 4 and 5. This pivoted handle has a flat section passing through elongated slots 116 and the rock shaft sleeve 106. The shaft axle slot 115 embraces the control handle loosely enough to permit it freedom of movement about its pivot, but snugly enough to be moved thereby in an endwise axial direction as the handle is swung from right to left, and the sleeve slots 116 are sufficiently long not to interfere with this swinging movement. Thus the rock shaft sleeve and axle together form a two-part rock shaft the parts of which rotate in unison by virtue of the passage of handle 112 and key 109 therethrough, but which parts are capable of relative endwise shifting in an axial direction. When the control handle 112 is in its right hand position it pulls rock shaft axle 108 to its right hand position and sets clutch key 109 in the clutch slots 110 and 111 of rocker arm sleeve 105. Depres-

sion of the handle 112 will then cause the rock shaft axle and rock shaft sleeve to rotate together and will twist clutch key 109 so as to turn the rocker arm sleeve 605 in a counter-clockwise direction as viewed in Fig. 6, thus raising arms 104, links 103, and the drill spindle carriage. Being free of rocker arm sleeve 605, the clutch key will not move the latter so long as the control handle is in its right hand position. However, when the latter is shifted to the left, it moves the rock shaft axle 108 and its clutch key 109 in that direction, engaging the latter with the slots 610 and 611 of the rocker arm sleeve 605. Subsequent depression of the control handle will then raise the screw driver carriage 595 in a manner similar to that in which the corresponding drill carriage was raised.

One of the links 103 for lifting the drill carries a button 117 (Fig. 4) which normally rests against and depresses a switch button 118 which controls the drill motor 38. The button 117 holds such switch open and the motor does not run until the drill has been raised sufficiently to clear button 117 from the switch. The drill accordingly rotates whenever it is lifted through control handle 112 and continues its rotation until it is again lowered to its initial position by such handle.

Means are provided for registering the clamped shoe precisely with the drill when the latter is elevated. This includes a cam 119 (Figs. 4, 5, and 6) fixed to the rocker shaft sleeve 106 and having a depression 120 at one point in its periphery. A roller on one end of a bell crank lever arm 121 rides on this cam and normally rests in such depression when the control handle 112 is in its uppermost position and the drill is in its normal lowermost retracted position. Depression of the control handle to raise the drill moves the bell crank lever arm 121 in a counter-clockwise direction. This lever is rockably mounted in a bearing 122 on the upper frame casting 24. It has a second arm 123 (Figs. 4 and 6) the end of which is forked to embrace a flattened section on the tail of a bullet detent 124. This detent is slideable in a guide bore in the upper frame casting and is normally biased downwardly by a spring 125. However, when the drill is elevated the attendant rotation of rocker shaft sleeve 106 imparts the described counter-clockwise movement to bell crank arms 121 and 123, and causes the latter to raise the bullet detent 124 against its spring bias into a recess 126 on the under face of the clamp base casting 30. This recess is so positioned with reference to the hollow last jack pin 43 that when it is held directly over the detent 124 the hollow bore in the last jack pin is in precise registry with the drill 86, and the latter can be raised with the assurance that it will pass accurately into the shoe. In drilling, the handle 112 is depressed until the shouldered upper end of drill spindle 87 abuts against the interior face of the insole. This can be felt by the operator who then lifts handle 112 and restores the drill to its initial lowermost position. The detent 124 also serves to prevent swinging movement of the clamp unit unless the drill is retracted so as to clear the clamp base. A further function of the cam depression 120 and its associated roller which is spring pressed by detent spring 125, is to hold the rock shaft in determined angular position when the handle 112 is left in its uppermost position.

After drilling, the shoe is ready to have a screw driven in the hole bored through its heel seat

material and into its heel. With his left hand, the operator takes a screw from a suitable trough 127 (Fig. 8) which may conveniently be cast in the upper frame casting and drops it head downward in a screw magazine socket 128 (Fig. 10) which is screwed in the upper frame casting 24 in alignment with the screw driver spindle 587. This socket has a bottom aperture 129 which is of sufficient diameter to pass the screw driver spindle, but is small enough to prevent the head of the screw from dropping therethrough. While it is not essential, the apertured bottom of the socket may comprise the core of an electromagnet 130 (Figs. 10 and 12) which is connected across the screw driver motor leads and serves to set the steel screw firmly against the bottom of the socket in position to be picked up by the driver when the latter is elevated. Preferably, although not essentially, a screw having deep multiple slots such as a "Phillips" or "Reed & Prince" screw and a corresponding driver are employed, as these afford more stability during the time the screw is being lifted on the driver through the last.

With the drilling operation completed and a screw placed in readiness within the magazine socket 128, the operator shifts the control handle 112 to the left bringing clutch key 109 into engagement with rocker arm sleeve 605, preparatory to rotating the latter to lift the screw driver spindle carriage 595. The shifting of the rock shaft axle 108 to the left also serves to swing the clamp unit to the left so as to bring the shoe into alignment with the driver. The means for doing this includes a groove 131 (Figs. 5 and 4) near the left end of rocker shaft 108, which here projects outwardly beyond rocker shaft sleeve 106, into which the opposed tines 132 of the forked end of a lever 133 are fitted. The lever 133 swings about a fixed pivot 134 on the frame casting and has an arm extending rearwardly beyond this pivot, which arm in turn is pivotally connected with a link 135. This link is pivoted to the arm 71 on collar 32 to which spring 76 is also connected. Axial movement of the rocker shaft 108 to the left accordingly causes the collar 32 to swing in a clockwise direction as viewed in Fig. 5 against its spring bias and this in turn imparts a clockwise swinging movement to the entire clamp unit, bringing the stud 79 to the left hand end of its arcuate slot 80, and bringing the hollow last jack pin 43 into substantial alignment with the screw socket 128 and the screw driver spindle 587. Exact registry of these parts is assured by a bullet detent 136 (Fig. 10) which is normally spring biased upwardly by a spring 137 into the path of the clamp base 30, which is adapted to override the nose of the bullet detent and allow the latter to snap into position in the recess 126. The detent 136 is positioned so as exactly to align the hollow jack pin and the screw driver spindle. With the clamp in this position, the control handle 112, as explained, is in its left hand position and the clutch key 109 is in engagement with the rocker arm sleeve 605 so that the handle 112 can again be depressed so as to rotate the clutch key 109 and lift the screw driver spindle carriage 595. This lifting continues until the screw driver picks up the screw in the magazine socket and brings it nearly to the insole, where a switch controlling the driver motor is closed so as to start it. The means for doing this includes a switch cam 138 (Figs. 4, 10, and 11) which is mounted on a stud 139 which extends outwardly

from one of the links 603 which lift the driver spindle carriage. A spring 140 urges a face of this switch cam against a friction washer 141 so that the cam is free to pivot about the stud 139, but tends to remain in any position to which it is pushed. The cam 138 has a sloping face 142 which on the upward movement of link 603 is adapted to wipe against the starting switch button 143 and close the driver motor circuit and start the motor 588. The cam has a tail 144 which, after the face 142 has wiped across the switch button 143 and started the motor, strikes and wipes against an abutment 145 on the frame. As is shown in dotted outline in Fig. 10, the wiping of tail 144 against this abutment during the latter portion of the lifting movement of the screw driver, tilts or cocks the cam 138 outwardly so that during the subsequent descending movement of the driver and its associated link 603, the sloping cam face 142 clears the starting button 143. The screw driver motor circuit, once closed by such button 143, has sustaining means, hereinafter described, so that the motor 588 continues to rotate the screw driver until it is cut off by another control switch about to be described. For this reason it is not desired to have the cam 138 wipe across the switch button 143 during its descent, as this would start the motor at an unwanted time. Near its lowermost position, the descending tail 144 strikes a second abutment 146 on the main frame which tilts the cam back to its initial position with its face 142 again in the path of starting switch button 143 for subsequent operation of such button the next time the driver is raised.

The screw driving action may be stopped by any suitable mechanism, such as a frictional slip-clutch between the screw driver pulley 589 and its drive sleeve 590, or a suitably calibrated actuating cam on the rock shaft 106, 108 for cutting out the screw driver motor. Preferably, however, the drill controlled motor stopping mechanism about to be described is employed.

The control switch for stopping the screw driver motor 588 is mounted on the frame strut 23 near the rock shaft sleeve 106. It has a push button 147 (Fig. 16) depression of which serves to open the driver motor circuit and stop rotation of the driver. The stop switch is of the so-called "micro-switch" type and movement of the button 147 through only a few thousandths of an inch serves to open and close the switch connection. The button accordingly can be employed as a precisely located limiting abutment. It is adapted to be depressed to stop the motor precisely at the moment when the top face of the screw head reaches the plane of the inner or foot engaging face of the insole. This point is measured by the shouldered drill spindle 87, it being recalled that during the drilling operation this spindle is lifted until its shouldered upper end bears against and is stopped by the face of the insole. In order to lift the drill spindle to this elevation the rock shaft sleeve 106 must be turned through a determined arc which is measured by the stop switch mechanism about to be described so that when the rock shaft again is turned through this same arc during the screw driving operation, the screw driver stop switch is engaged and depressed at precisely the proper point along the arc of rotation of rock shaft sleeve 106. The means for doing this includes a slip collar 148 which is clamped by a spring 149 in frictionally gripping but freely rotatable relation with rock shaft sleeve 106. The

slip collar tends to turn with this sleeve, but can slip with respect thereto if it is pushed with sufficient force to overcome its frictional grip. The slip collar 148 has a rearwardly projecting arm 150 carrying an adjustable stop screw 151 which is adapted to abut and depress switch button 147. Preferably a pin 152 carried by the arm 150 also engages the frame substantially coincidentally with the depression of switch button 147, acting as a positive limiting stop to relieve the latter of excessive pressure. With this arrangement, when the control handle 112 is first depressed in its right hand position so as to lift the drill spindle 87, the rocking movement thus imparted to rock shaft sleeve 106 carries the slip collar 148 around with such sleeve until the screw 151 just reaches and depresses the switch button 147 (which at this time is in a dead circuit). The slip collar stops at this point and any further movement imparted to the rock shaft sleeve 106 merely causes the latter to slip around within the now stationary collar 148. Thus in bringing the shouldered drill spindle 87 into abutting contact with the inner face of the insole, the rock shaft and its slip collar will be given a determined mutual angular relation which is determined by the vertical height to which the drill spindle was raised, which in turn is determined by the individual dimensions of each shoe. When the drill spindle has been fully raised until it is stopped by the insole, subsequent retraction of this spindle and lifting of the control handle 112 causes clockwise movement of the rock shaft sleeve 106 (Fig. 16) which is shared by the slip collar 148. During this movement the arm 150 falls away from the switch button 147. During the subsequent screw driving operation, the control handle is again depressed, this time in its left hand position, so as to raise the screw driver spindle 587. This causes closing of the driver motor start switch 143 by the cam 138 and a sustaining circuit keeps such motor energized until it is cut out by the depression of stop switch button 147. This is effected when the rock shaft sleeve 106 repeats the lifting arc which has been measured by the previous abutment of screw 151 against switch button 147 and at the completion of this lifting arc such screw again abuts and depresses the stop switch button, stopping the driving motor. The screw driver spindle 587 and its associated screw driver are so dimensioned that the head of the screw is lifted to exactly the same horizontal plane that the shoulder on the drill spindle occupied at its uppermost position, in other words, the plane of the face of the insole of the clamped shoe. At this point the stop switch button 147 is reached and depressed.

Means is provided for assuring measuring contact between the screw 151 and the switch button 147 during each drilling operation regardless of the nature of possible variations in the heights of successive shoes. This includes a second arm 153 carried by the slip collar 148. When the control handle 112 is in its uppermost position prior to a drilling operation, this arm 153 is in the path of a slideable push rod 154 mounted on the frame and normally spring biased to a rearward retracted position by a spring 155. The inner end of push rod 154 is adapted to be engaged by a roller 156 carried on a T-shaped lever which is pivoted at 157 to the machine frame. A link 158 connects this lever with a lever arm 159 (Fig. 2) fastened to a rock shaft 160 to which a clamp thruster control treadle 161 is also fastened.

The rock shaft 160 also carries an arm 162 which upon depression of the treadle 161 wipers against and depresses a switch button 163 which closes the circuit through and energizes a thruster motor 164. So long as the treadle 161 is held depressed, this motor continues to rotate and this in turn lifts and holds lifted the thruster rod 81, thus opening the clamp by lifting the clamp rod 34.

Thus each time the clamp is opened the push rod 154 is moved forwardly against its spring bias by the roller 156 so as to engage the arm 153 on slip collar 148 and slip the latter in a counter-clockwise direction with respect to the rocker shaft 106, which at this time remains stationary with control handle 112 in its uppermost position. This slip movement of the collar brings the arm 150 somewhat toward the stop switch push button 147 and makes certain that the latter will be reached by the screw 151 during subsequent depression of control handle 112 during the next drilling operation.

A brake is provided for assuring prompt stopping of the rotation of the screw driver upon opening of the stop switch button 147. This includes a friction shoe 164 (Fig. 4) adapted to bear in rubbing contact against the face of the screw driver pulley 589. This shoe is pivotally carried by a lever 165 pivoted at 166 to the bearing column 591. The lever 165 is normally biased downwardly by a spring 167 seated between such lever and a spring seat attached to the bearing column 91. The lever 165 is held raised against such bias so as to lift the brake shoe clear of pulley 589 during rotation of the screw driver by a solenoid 168 which is connected across the leads of the screw driver motor 588. The armature 169 of this solenoid is pivotally linked to the lever 165 and holds the latter in elevated non-braking position until such time as the screw driver stop switch button 147 is depressed, whereupon the lever 165 is released, thus promptly braking the screw driver spindle to a stop.

After completion of the screw driving operation, the control handle 112 is again elevated, retracting the driver spindle 587 to its lowermost position where it clears the shoe and the clamp base. The thruster treadle 161 is then depressed again, opening the clamp by lifting clamp rod 34 and arm 38, whereupon the shoe is removed and racked. The thruster treadle 161 is then released allowing the clamp to close under the bias of its spring 37. Inasmuch as the clamp is now emptied, the arm 38 will be sent to its lowermost position until it is limited by engagement against the top of clamp post 28. This brings the lifting cap 35 to its lowermost position which is somewhat lower than its previous location during the time a shoe and heel were loaded in the clamp. This additional lowering of the cap 35 is utilized to release the clamp holding detent 136 and allow the clamp unit automatically to return to drilling position under the bias of its spring 76. The means for doing this includes an arm 170 (Fig. 10) fixed to the rock shaft 84 which carries the lifting lever 83. The outer end of arm 170 is pinned in a loose motion slot 171 of a link 172 pivoted at its upper end to a lever 173 swingable about a fixed pivot 174 in the upper frame casting. The lever 173 has a rearwardly extending flattened arm 175 seated between the end shoulders of a flat portion 176 on the tail of detent 136. An additional arm 177 is carried on lever 173 in position to be engaged and depressed, when wanted, by a manual push rod 178. The

arrangement is such that when the thruster rod 81 is lifted to insert a shoe at the drilling station, the arm 170 rides freely in loose motion slot 171 leaving the bullet detent 136 at the driving station projected under its spring bias. When the thruster is allowed to settle back so as to clamp the shoe, the lever 83 and arm 170 will come to rest with the pin of arm 170 engaging against and arrested by the upper end of slot 171, the strength of spring 137 and the weight of parts 170, 172, and 173 being sufficient to overbalance the weight of lever 83. When the clamp is closed at the drilling station, the lifting cap 35 does not quite reach the roller 85 which settles under its own weight as the thruster rod 81 sinks until it is stopped by the arm 170 bearing against the upper end of slot 171. When the clamped shoe is swung to the screw driving station, the recess 126 in the clamp base 30 rides over the bullet detent 136, as described, and this detent remains in place during the succeeding driving operation. When, however, the screw driving is completed and the clamp is opened at the driving station and the shoe removed, subsequent lowering of the clamp rod 34 brings the cap 35 into downward pushing engagement against the roller 85 turning arm 170 slightly so as to retract the bullet detent 136. As soon as this happens, the spring 76 is free to return the clamp unit to its normal initial position at the drilling station and the spring 76 also restores the control handle 112 to its right hand position through the linkage 135, lever 133, etc. Accordingly, the clamp arrives in closed condition at the drilling station ready to be opened by the foot treadle 161 for a repeated loading, drilling and screw driving cycle of operations.

One suitable form of circuit for controlling the electrically operated parts of the machine is shown in Fig. 17. Here current is led from a suitable source such as a single phase line having leads L₁, L₂, to a main line switch 179. The clamp thruster motor switch push button 163 is adapted to close its associated switch 180 whenever the treadle 161 is depressed. This passes current from L₁ through a lead 181 through the now closed switch 180 through the thruster motor 164 and back through a lead 182 to L₂. So long as motor 164 is energized, the thruster rod 81 is raised and held raised by the action of its hydraulic impeller and piston, and as soon as the motor 164 is de-energized by release of treadle 161 such rod settles back to its lowermost position allowing the clamp to close. With a shoe clamped in position at the drilling station and the clamp motor 164 de-energized through release of the foot treadle, the operator is ready to elevate the drill and start the drill motor. He does this by depressing control handle 112, lifting the button 117 from the path of push button 118 of the drill motor start and stop switch 183, enabling current to pass from L₁ through lead 181 to a lead 184 through the now closed switch 183 and the drill motor 88 and back through a lead 185 to lead 182 and L₂. The drill motor continues rotation as long as the button 117 is raised above switch button 118, and stops as soon as button 117 returns to its normal position. With the drilling operation completed, the operator moves control handle 112 to the left, bringing the clamped shoe in alignment with the screw driver. The control handle 112 is then depressed causing cam 138 to depress the driver motor start switch button 143. This closes the driving switch 186 passing current from L₁ through lead 181 through

a lead 187 and the now closed driver start switch 186 and through the coil 188 of a magnetic switch 189, and thence back to lead 182 and L₂. Once the driver start switch button 143 has been depressed to energize the coil 188, the magnetic switch 189 closes, passing current from L₁ to terminal T₁ through switch 189 to a motor lead 190 through the screw driver motor 588 and back through a lead 191 through switch 189 to terminal T₂ of L₂.

A sustaining circuit for the magnetic switch comprises a lead 192 from terminal T₁ to the screw driver motor stop switch designated 193. The push button 147 of this switch 193 normally leaves the latter closed so that once the magnetic coil 188 has been energized so as to close switch 189, current passes through T₁ and lead 192, through normally closed stop switch 193 to the coil 188 and back to lead 182 and L₂. Once this sustaining circuit is set up the driver start button 143 can be released to open switch 186, which occurs when the cam 138 wipes past and clears such button 143. Thereafter the screw driver motor 588 is stopped by depression of switch button 147 of stop switch 193 when such button 147 is engaged by the screw 151 on slip collar 148.

The coil of brake solenoid 168 and the coil of the screw socket magnet 130 are respectively connected across the screw driver motor leads 190 and 191 so that these coils are energized concurrently with such motor.

The operation is largely apparent from the foregoing description but may be briefly reviewed. In its normal condition the clamp unit and its associated control handle 112 is swung to its right hand position and the control handle is also in its uppermost position. The operator now steps on treadle 161, energizing the thruster motor 164 and lifting the clamp rod 34 which remains elevated and holds the clamp open so long as he leaves his foot on treadle 161. A lasted shoe is now inverted over the hollow last jack pin 43 and its heel is seated by hand over its heel seat, which has previously been cut on and prepared for reception of the heel. Cement may or may not be applied before the screwing operation, as desired. In preferred practice, it is found that cement is not needed. The operator now releases treadle 161 allowing the top-lift and back-heel clamps 41 and 42 to bear against the heel and hold it in place. Control handle 112 is now depressed, causing cam 119 to raise detent 124 into recess 126 to hold the clamp base firmly in exact registry with the drill during the ascent of the latter. Continued depression of handle 112 lifts the drill spindle 87 through the aperture in the last and drills through the heel seat materials into the heel until the shouldered end of the spindle engages the insole. The extent of the depression of handle 112 needed to impart this lifting movement to the drill is measured by the slip collar 148. After drilling, the operator returns the handle 112 to its uppermost position, freeing detent 124 from recess 126 and enabling the operator to shift the control handle to the left, thus engaging clutch bar 109 with the screw driver lifting carriage and also swinging the clamp unit into alinement with the driver where bullet detent 136 snaps into recess 126. The control handle is now depressed in its left hand position, starting the driver motor and lifting the driver until the latter screws the wood screw inserted in socket 128 home flush with the inner face of the insole, which position is determined by the slip collar 148 and its associated driver

motor stop switch. When the screw driver stops its driving movement this can be felt by the operator who again elevates the control handle 112 and lets it go to remove and rack the shoe. To this end, the treadle 161 is again depressed, opening the clamp, and when the treadle 161 is released to allow the clamp to close this complete closing movement retracts detent 136 from recess 126 and allows the closed clamp to swing to the right into alinement with the drill where it is ready to be opened and loaded with a new shoe and heel for a further attaching operation.

It will be seen that a heel attaching machine has been provided which is capable of inserting 15 a fastener rapidly and accurately in the heel of a lasted shoe and that such machine is subject to easy control through a foot treadle and single operating lever, which simplifies the work of the operator and enables him to attain a high daily 20 rate of production. The machine inserts a permanent fastener in the shoe which holds the heel attached during the final stages of shoe manufacture and also is useful in affording a strong attachment during wear. Preferably, in addition 25 to the permanent wood screw the usual five heeling nails also are driven into the heel after the shoe is delasted, although this may be dispensed with if wanted.

It will be understood that certain changes 30 could be made in the form of machine which is illustrated by way of example without departing from the scope of the invention. Thus instead of an hydraulic thruster any equivalent lifting means such as an electric drive motor and suitable gear train and pitman could be used to impart 35 the desired reciprocatory movement to clamp rod 34. The clamp construction itself has novel features which can be used to advantage in various kinds of heel treating machines and which 40 need not necessarily be combined with the particular drill and driver illustrated. The clamp also, if wanted, could be mounted on a fixed frame, in which case the drill and driver could be carried by a swinging frame for selective alinement 45 with the clamped shoe. If wanted, instead of using a wood screw, the screw lifting spindle could be used to press fit a rivet or nail or like fastener, in which case the fastener inserting spindle would not have to be rotated.

The mechanism whereby the drilling operation 50 is utilized to measure and control the extent of the related driving operation is of general utility in various related operations and is broadly claimed in my co-pending joint application with John F. Smith, Serial No. 394,836, filed May 23, 1941, which has matured as Patent Number 2,306,787 of December 29, 1942.

Since certain changes may be made in the 55 above construction and different embodiments of the invention could be made without departing from the scope thereof, it is intended that all matter contained in the above description or shown in the accompanying drawings shall be interpreted as illustrative and not in a limiting sense.

It is also understood that the following claims 60 are intended to cover all of the generic and specific features of the invention herein described, and all statements of the scope of the invention, 65 which, as a matter of language, might be said to fall therebetween.

Having described my invention, what I claim 70 as new and desire to secure by Letters Patent is:

1. In a heel attaching machine, the combination 75 comprising, a frame, a drill and a driver

mounted on said frame, a clamp for holding a shoe and heel together swingably mounted on said frame, means normally urging said clamp in shoe holding position, and means for successively alining a shoe and heel held by said clamp in operative relation with respect to said drill and driver.

2. In a heel attaching machine, the combination comprising a frame, a drill and a driver movably mounted on said frame, a clamp normally biased to hold a shoe and heel together swingably mounted on said frame for movement between positions respectively in operative alinement with said drill and driver, means for rotating said drill, and means for successively moving said drill and driver into operative relation with a shoe and heel held by said clamp.

3. In a heel screwing machine, the combination comprising, a frame, a drill and a screw driver mounted for vertical movement on said frame, a clamp normally biased to hold a shoe and a heel mounted for horizontal swinging movement on said frame between positions respectively in operative alinement with said drill and driver, means for rotating said drill and said driver, and means for successively raising and lowering said drill and driver into operative relation with a shoe and heel held by said clamp.

4. A heel attaching machine, comprising, in combination, a frame, a drill and a driver movably mounted on said frame, a clamp for holding a shoe and heel together mounted on said frame for movement between positions respectively in operative alinement with said drill and driver, means for rotating said drill, an operating handle, and connections between said handle and said drill, driver and clamp for successively moving a shoe and heel held by said clamp into operative alinement with said drill and driver and for successively moving said drill and driver into operative relation with said shoe and heel.

5. A heel attaching machine according to claim 4, having means for controlling said drill rotating means through said operating handle.

6. In a heel attaching machine, the combination comprising, a frame, spaced drill and driver elements mounted on said frame, a clamp normally biased to hold a shoe and heel together movably mounted on said frame, means biasing said clamp normally into operative alinement with one of said elements, and means for moving said clamp into operative alinement with the remaining element.

7. In a heel attaching machine, the combination comprising, a frame, spaced drill and driver elements each vertically reciprocable on said frame, a clamp for holding a shoe and heel together horizontally swingable on said frame, means biasing said clamp normally into alinement with one of said elements, and means including a single control handle for swinging said clamp into operative alinement with the remaining element and for selectively raising and lowering said drill and driver elements.

8. In a heel attaching machine, the combination comprising, a fixed frame member having an upper horizontal surface and a swingable member pivoted about a vertical axis for swinging movement on said surface, clamping means for holding a shoe and a heel together carried on one of said members, and a drill and a driver carried by the other member, a foot operated control means for opening and closing said clamping means, and means including a single manual operating lever for swinging said swingable member

about its axis selectively to aline said drill and driver with a shoe held by said clamping means.

9. In a heel attaching machine, the combination comprising, a fixed frame member having a vertical bearing therein, a swinging member mounted for horizontal oscillatory movement in said bearing, clamping means normally biased to hold a shoe and a heel together carried on one of said members and a drill and a driver carried on the other member, means for reciprocating said drill and said driver selectively into operative relation with a shoe held by said clamping means, and means for moving said swinging member selectively to aline said shoe with said drill and driver.

10. In a heel attaching machine, the combination comprising, a fixed frame member having a vertical bearing therein, a swinging member mounted for horizontal oscillatory movement in said bearing, clamping means for holding a shoe and a heel together carried on one of said members and a drill and a driver carried on the other member, means for reciprocating said drill and said driver selectively into operative relation with a shoe held by said clamping means, and means for moving said swinging member selectively to aline said shoe with said drill and driver, the means for reciprocating said drill and driver and for swinging said swinging means including a single common control for said named parts.

11. In a heel attaching machine, the combination comprising, a fixed frame member having a vertical bearing therein, a swinging member mounted for horizontal oscillatory movement in said bearing, clamping means normally biased to hold a shoe and a heel together carried on one of said members and a drill and a driver carried on the other member, means for moving said swinging member between drilling and driving positions at either end of its swinging arc, locking means for holding said swinging member selectively at either of said positions, means for reciprocating said drill and driver selectively into operative relation with a shoe held by said clamping means, and means for axially rotating said drill.

12. In a heel attaching machine, the combination comprising, a fixed frame member having a vertical bearing therein, a swinging member mounted for horizontal oscillatory movement in said bearing, clamping means for holding a shoe and a heel together carried on one of said members and a vertically reciprocable drill and driver each carried on the other member, a control handle, connections between said handle and swinging member for moving the latter between opposite limits of its swinging arc, and connections between said handle and said drill and driver for reciprocating the latter respectively into operative relation with a shoe held by said clamping means when said swinging member is at corresponding respective limits of its swinging arc.

13. In a heel attaching machine, the combination comprising, a fixed frame member having a vertical bearing therein, a swinging member mounted for horizontal oscillatory movement in said bearing, clamping means for holding a shoe and a heel together carried on one of said members and a vertically reciprocable drill and driver each carried on the other member, means biasing said swinging member to one limit of its swinging arc, a control handle, connections between said handle and swinging member for

moving the latter against its bias to the other limit of its swinging arc, connections between said handle and said drill and driver for reciprocating the latter respectively into operative relation with a shoe held by said clamping means when said swinging member is at corresponding respective limits of its swinging arc, and means for opening and closing said clamping means.

14. In a heel attaching machine, the combination comprising, a fixed frame member having a vertical bearing therein, a swinging member mounted for horizontal oscillatory movement in said bearing, clamping means for holding a shoe and a heel together carried on one of said members and a vertically reciprocable drill and driver each carried on the other member, clamp opening and closing means for said clamping means, means biasing said swinging member to one limit of its swinging arc, a control handle, connections between said handle and swinging member for moving the latter against its bias to the other limit of its swinging arc, connections between said handle and said drill and driver for reciprocating the latter respectively into operative relation with a shoe held by said clamping means when said swinging member is at corresponding respective limits of its swinging arc, a detent for holding said swinging member against its bias, and means governed by said clamp opening and closing means for releasing said detent.

15. In a heel attaching machine, the combination comprising, a fixed frame member having a vertical bearing therein, a swinging member mounted for horizontal oscillatory movement in said bearing, clamping means for holding a shoe and a heel together carried on one of said members and a vertically reciprocable drill and driver each carried on the other member, clamp opening and closing means for said clamping means, means biasing said swinging member to one limit of its swinging arc, a control handle, connections between said handle and swinging member for moving the latter against its bias to the other limit of its swinging arc, connections between said handle and said drill and driver for reciprocating the latter respectively into operative relation with a shoe held by said clamping means when said swinging member is at corresponding respective limits of its swinging arc, a detent for holding said swinging member in its biased position, means governed by said handle for moving said detent into operative position, a second detent for holding said swinging member against its bias, and means governed by said clamp opening and closing means for releasing said second detent.

16. In a heel attaching machine, the combination comprising, a frame, a drill and a driver reciprocable on said frame, a clamping unit swingably mounted on said frame about an axis equidistant from said drill and driver, said unit having opposed relatively movable clamping parts normally biased towards each other to hold a shoe and heel therebetween, means for selectively swinging said clamping unit into alignment with said drill and driver, means for opening and closing said clamping parts, and means for selectively reciprocating said drill and driver into operative relation with an aligned shoe held by said clamping parts.

17. In a heel attaching machine, the combination comprising, a frame, a drill and a parallel driver reciprocable on said frame, a clamping unit swingably mounted on said frame about an axis parallel with and equidistant from said drill and

driver, said unit having opposed relatively movable clamping parts for holding a shoe and heel therebetween, means for selectively swinging said unit into alignment with said drill and driver, means on said frame and aligned with the swinging axis of said clamping unit arranged to open and close the clamping parts of the latter in either named position thereof, and means for selectively reciprocating said drill and driver into operative relation with an aligned shoe held by said clamping parts.

18. In a heel attaching machine, the combination comprising, a frame, a drill and a parallel driver reciprocable on said frame, a clamping unit swingably mounted on said frame about an axis parallel with and equidistant from said drill and driver, said unit having opposed relatively movable clamping parts and a spring normally urging said parts together to hold a shoe and heel therebetween, means for selectively swinging said unit into alignment with said drill and driver, means on said frame operable along the swinging axis of said clamping unit to open the clamping parts of the latter in either named position thereof, and means for selectively reciprocating said drill and driver into operative relation with an aligned shoe held by said clamping parts.

19. In a heel attaching machine, the combination comprising, a frame, a drill and a driver mounted thereon, a clamping unit movably mounted on said frame for selective alignment with said drill and driver, relatively movable work engaging clamping parts on said unit for holding a shoe and heel therebetween, a spring on said unit urging said parts into work holding position, means on said frame for opening said parts against their spring bias, and means for selectively effecting relative approach of a shoe held by said clamping unit and of said drill and driver into operative relation with one another.

20. In a heel attaching machine, the combination comprising, a frame, a drill and a driver mounted thereon, a clamping unit movably mounted on said frame for selective alignment with said drill and driver, relatively movable work engaging clamping parts on said unit for holding a shoe and a heel therebetween, means on said frame for opening and closing said clamping parts, and means for selectively effecting relative approach of said drill and driver and of a shoe held by said clamping unit into operative relation with one another.

21. In a heel attaching machine, the combination comprising, a frame, a drill and a driver reciprocable on said frame, a clamping unit movably mounted on said frame for selective alignment with said drill and driver, relatively movable work engaging parts on said unit normally biased towards each other to hold a shoe and a heel therebetween, means on said frame for opening said clamping parts, and means for selectively reciprocating said drill and driver into operative relation with a shoe held by said clamping parts.

22. In a heel attaching machine, the combination comprising, a frame, a drill and a driver reciprocable on said frame, a clamping unit movably mounted on said frame for selective alignment with said drill and driver, relatively movable work-engaging parts on said unit for holding a shoe and a heel therebetween, means for opening and closing said clamping parts, means for selectively reciprocating said drill and driver into operative relation with a shoe held by said clamping parts, and an operating lever for actuating and controlling said reciprocating means.

23. In a heel attaching machine, the combination comprising, a frame, a drill and a driver reciprocable on said frame, a clamping unit movably mounted on said frame, means for moving said clamping unit into selective alignment with said drill and driver, relatively movable work-engaging parts on said unit for holding a shoe and a heel therebetween, means for opening and closing said clamping parts, means for selectively reciprocating said drill and driver into operative relation with a shoe held by said clamping parts, and a single operating lever for actuating and controlling said clamp moving means and said reciprocating means.
24. In a heel attaching machine, a frame, a drill and a driver mounted for reciprocation on said frame, a shoe and heel holding clamping unit movably mounted on said frame for selective alignment with said drill and driver, a shiftable operating lever, connections respectively attached to said drill and said driver for reciprocating them, and clutch means selectively coupling said lever with said drill or driver connections.
25. In a heel attaching machine, a frame, a drill and a driver reciprocable on said frame, a shoe and heel holding clamping unit movably mounted on said frame, a shiftable operating lever, connections between said operating lever and clamping unit for selectively moving said unit into alignment with said drill and driver, and clutch means selectively coupling said lever with said drill and driver to reciprocate them into operative relation with a shoe and heel held by said clamping unit upon manipulation of said lever.
26. In a heel attaching machine, a frame, a drill and a driver reciprocably mounted on said frame, a shiftable rock shaft on said frame, a pair of adjoining rocker arm sleeves on said shaft, means connecting the rocker arm of one of said sleeves with said drill and means connecting the rocker arm of the remaining sleeve with said driver, means for shifting said shaft selectively into coupled relation with either of said sleeves, and means for rotating said shaft and its coupled sleeve to reciprocate said drill or driver.
27. In a heel attaching machine, a frame, a pair of parallel bearing columns on said frame, carriages respectively slidable in said columns, a drill carried by one of said carriages and a driver carried by the other, means for rotating said drill, a rock shaft on said frame, means for rocking said shaft, connections from said shaft to said carriages for sliding the latter along their columns, and means for holding a shoe and heel in the paths of said drill and driver.
28. In a heel screw attaching machine, a frame, a pair of parallel bearing columns on said frame, carriages respectively slidable in said columns, a drill carried by one of said carriages and a screw driver carried by the other, means for rotating said drill and said driver, a rock shaft on said frame, rocker arms adapted to be carried with said rock shaft, means for rocking said shaft, links respectively connecting said arms with said carriages, and means for holding a shoe and a heel in the paths of said drill and driver.
29. In a heel attaching machine, a frame, a pair of parallel bearing columns on said frame, carriages respectively slidable in said columns, a drill carried by one of said carriages and a driver carried by the other, means for rotating said drill, a rock shaft on said frame, means for rocking said shaft, a pair of rocker arm sleeves freely rotatable on said rock shaft and each carrying links respectively connecting said arms with said carriages, clutch means selectively coupling said rock shaft with either of said sleeves, and means for holding a shoe and heel in the paths of said drill and driver.
30. In a heel screw attaching machine, a frame, a drill and a screw driver reciprocably mounted on said frame, a shoe and heel clamping unit movable on said frame, driving means for rotating said drill and driver, mechanism for moving said clamping unit into alignment with said drill or driver, connections respectively attached to said drill and driver for reciprocating them into operative relation with work held by said clamping unit, an operating control lever, and means for operatively coupling said lever with said driving means to start and stop the latter, with said mechanism to move said clamping unit, and with said connections to reciprocate said drill and driver.
31. In a heel attaching machine, a frame, a drill and a driver movable on said frame, a clamping unit movable on said frame for selectively holding a shoe and heel in the respective paths of said drill and driver, a two part rock shaft including a rock shaft sleeve rotatable on said frame and a rock shaft axle within said sleeve adapted to rotate in unison therewith and capable of endwise shifting movement with respect thereto, connections from said rock shaft to said drill and driver respectively for moving the latter into operative relation with said shoe and heel, clutch means actuated by said rock shaft axle for selectively coupling the latter with either of said connections upon endwise shifting of said axle, and means for rotating said rock shaft and for imparting shifting movement to said rock shaft axle.
32. In a heel attaching machine constructed in accordance with claim 31, the combination wherein mechanism actuated by shifting movement of said rock shaft axle is provided for moving said clamping unit between its respective work stations.
33. In a machine for attaching a heel to a shoe lasted on a last having its jack-pin hole extended therethrough, a frame having a driver reciprocable thereon, an apertured fastener receiving socket aligned with said driver, a clamping unit on said frame having a hollow jack-pin and a cooperating top-lift clamp adapted to hold a lasted shoe and a heel therebetween, said hollow jack-pin being aligned with said driver and socket, and means for reciprocating said driver through said socket, jack-pin, and last, whereby it can pick up a fastener loaded in said socket and drive it into the shoe and heel.
34. In a machine for attaching a heel to a shoe lasted on a last having its jack-pin hole extended therethrough, a frame having a screw driver reciprocably mounted thereon, a clamping unit on said frame having a hollow last receiving jack-pin aligned with said driver and a cooperating clamp part adapted to hold a heel against a lasted shoe seated over said jack-pin, means for rotating said screw driver, and means for reciprocating said screw driver through said jack-pin and last to insert a fastener through the shoe and into the heel.
35. In a machine for attaching a heel to a shoe lasted on a last having its jack-pin hole extended therethrough, a frame having a driver reciprocable thereon, an apertured fastener receiving socket on said frame in the path of said driver, a clamping unit movable on said frame having a hollow jack-pin and a top lift clamp adapted to

hold a shoe and heel therebetween, and means for registering said jack pin and socket.

36. In a machine for screwing a heel to a shoe lasted on a last having its jack-pin hole extended therethrough, a frame, a screw driver reciprocably mounted on said frame, a socket in said frame for holding an inverted headed screw and having an aperture in its bottom permitting passage of said driver, a clamping unit comprising a hollow jack-pin and a cooperating heel clamp for holding a shoe and heel therebetween, said screw driver, socket, and jack pin being in alignment during a screw driving operation, and means for rotating said screw driver.

37. In a machine for attaching a heel to a shoe lasted on a last having its jack-pin hole extended therethrough, a drill and a driver each reciprocable on said frame, a clamping unit movable on said frame having a hollow jack-pin and an opposed heel clamp adapted to hold a lasted shoe and a heel therebetween, means for moving said clamping unit to bring said hollow jack-pin successively into registry with said drill and driver, and means for successively reciprocating said drill and driver through said jack-pin and into the last jack-pin hole.

38. In a heel treating machine, a frame, a heel clamping unit including relatively movable work engaging clamp parts, means movably mounting said unit on said frame for movement between different work stations, spring means urging and relatively moving said clamp parts into closed work holding position, and means on the frame for moving said work engaging clamp parts relatively apart against their spring bias.

39. In a heel treating machine, a frame, a heel clamping unit including relatively movable work engaging clamp parts, said unit being pivoted on said frame for movement between different work stations, spring means on said unit urging said clamp parts together, and means on said frame for opening said clamp parts against their spring bias, said clamp opening means being operatively engageable with said unit along its pivotal axis whereby it may engage and open the clamp parts of the clamping unit while the latter is at different work stations.

40. In a heel treating machine, a frame, a clamping unit having a relatively movable top-lift clamp and a base carrying a shoe support for holding a shoe and heel therebetween, spring means on said unit for urging and moving said top-lift clamp and shoe support together, means pivoting said unit on said frame for movement between different work stations, and means on the frame for moving said clamp and shoe support relatively apart against their spring bias.

41. In a heel treating machine, a fixed frame, a clamping unit having a relatively movable top-lift clamp and a base carrying a shoe support for holding a shoe and heel therebetween, a pivot connecting said frame and unit for swinging movement of the latter between different work stations, and means on said fixed frame operable along the axis of said pivot for relatively opening and closing said clamp and support while said unit is at any of said work stations.

42. In a heel treating machine, a frame, a clamping unit having a base carrying a shoe support and a reciprocable top-lift clamp opposed to said support, a pivot connecting said frame and unit for swinging movement of the latter between different work stations, a rod passing slidably through said pivot and carrying said top-

lift clamp, and means on the frame for reciprocating said rod.

43. In a heel treating machine, a frame, a clamping unit having a base carrying a shoe support and a reciprocable top-lift clamp opposed to said support, a pivot connecting said frame and unit for swinging movement of the latter between different work stations, a rod passing slidably through said pivot and carrying said top-lift clamp, spring means carried with said unit urging said clamp toward said shoe support, and means on the frame for moving said rod to move said top-lift clamp against its bias away from said support.

44. In a heel treating machine, a frame having a vertical bearing therein, a clamping unit comprising a clamp base mounted for horizontal swinging movement and having a pivot in said bearing, a shoe support on said clamp base, a rod slidable through said pivot and bearing, a top-lift clamp carried at the upper end of said rod above said shoe support, a spring between said clamp base and rod urging the latter downwardly, and means on the frame for engaging and lifting said rod.

45. In a heel treating machine, a fixed frame, a clamping unit comprising a clamp base having an upstanding hollow post thereon, a shoe support on said base, a rod slidable through said post, means pivoting said unit to said frame along the axis of said rod for swinging movement of the unit between different work stations, a top-lift clamp carried by said rod opposite said support, means carried by said unit for reciprocating said rod axially in one direction relatively to said clamp base, and means on said frame for reciprocating said rod in the opposite direction.

46. In a heel treating machine, a fixed frame having a vertical bearing therein, a clamp base having an aligned upstanding post and depending pivot fixed thereto with said pivot rotatable in said frame bearing, a shoe support on said clamp base, a rod slidable through said post, clamp base, and pivot, an arm on the upper end of said rod above said post, a top-lift clamp on said arm overhanging said shoe support, a spring seat on said pivot and another spring seat therebeneath on the lower end of said rod, a compression spring between said seats, and means on said frame in alignment with and operable to lift said rod.

47. In a fastening inserting machine, a reciprocating drill, a reciprocating fastening-inserting device, a work-support initially positioned and retained against movement to receive the action of the drill, and means for moving the support to a position to receive the action of the inserting device, holding it against movement during such action and then returning it to its initial position at the drill.

48. In a fastening-inserting machine, a reciprocating drill, a reciprocating fastening-inserting device, a work-support initially positioned to receive the action of the drill, and means for moving the support to a position to receive the action of the inserting device, for returning it to its initial position at the drill and for retracting the device for the return of the support.

49. In a fastening-inserting machine, a reciprocating drill, a reciprocating fastening-inserting device, a work-support, means urging said work-support to a position to receive the action of the drill, and means for moving said work-support to a position to receive the action of the inserting device, for holding it against movement during inserting such action and for retracting the

device to allow said urging means to return it to its position at the drill.

50. In a fastening-inserting machine, a reciprocating drill, a reciprocating fastening-inserting device, a work-support initially positioned and retained against movement to receive the action of the drill, and means for reciprocating said drill, for moving said support to a position to receive the action of said inserting device, for reciprocating said inserting device and for returning said support to its initial position at the drill. 10

51. In a fastening-inserting machine, a reciprocating drill, a reciprocating fastening-inserting device, a work-support initially positioned and retained against movement to receive the action of 15

the drill, and means for moving said work support to a position to receive the action of the inserting device and for storing energy for returning it to its initial position at the drill.

52. In a fastening-inserting machine, a reciprocating drill, a reciprocating fastening-inserting device, a work-support initially positioned and retained against movement to receive the action of the drill, and means for moving said work-support to a position to receive the action of the inserting device, for storing energy for returning it to its initial position at the drill and for retracting the device for permitting the return of the support.

KENNETH W. MACDONALD.
